UNITED STATES PATENT OFFICE.

JAMES THOMAS, OF JOLIET, ILLINOIS.

RAIL-SPLICER.

No. 918,793.

Specification of Letters Patent Patented April 20, 1909.

Application filed December 21, 1908. Serial No. 463,433.

To all whom it may concern:

Be it known that I, JAMES THOMAS, citizen of the United States, residing at Joliet, in the county of Will and State of Illinois, have invented certain new and useful Improvements in Rail-Splices; and I do hereby declare that the following is a full, clear, and exact description of the invention, which will enable others skilled in the art to which it appertains to make and use the same.

This invention relates to a rail splice.

An object of the invention is to provide a rail splice that can be readily and easily produced in rolling mills; one that is very simple in construction and of low cost.

A further object is to provide a supporting base in the form of a channel to receive the rail and its parts and provide means for preventing longitudinal movement of said parts and the base relatively.

Another object is to improve upon the construction of the splice forming the subject matter of my application for rail splice filed November 18, 1908, Serial No. 463,329.

The present invention contemplates a base-plate for supporting the rail the same having an upturned flange at each longitudinal edge, the inner or facing surfaces of the said flanges being undercut so as to constitute an overhang for receiving splice-bars placed at each side of the rail one of said portions adapted to fit one of the undercut flanges, provision being made to prevent longitudinal movement of the two splice-bars relative to the base but this will be more clearly and fully explained hereinafter.

To the end that my invention may be understood I have provided the accompanying drawing in which:

Figure 1 is a transverse section of a rail, supporting base and other parts showing my invention in connection therewith. Fig. 2 is a perspective view of the same. Fig. 3 is a plan of the same. Fig. 4 is a perspective view of a portion of a splice-bar showing a notch therein. Fig. 5 is a vertical transverse section of a portion of the base-plate and a portion of a splice-bar showing a member or block for preventing longitudinal movement of the splice-bar and base relatively. Fig. 6 is a perspective view of the block shown in Fig. 5. Fig. 7 is a vertical transverse section of part of the base and part of a splice-bar showing a wedge shaped bolt illustrated in Fig. 1.

The rail is represented by the letter A, and

B is a base-plate constituting a support for the rail. Said plate is provided with an upturned flange at each longitudinal edge represented by C and C' whose inner or facing surfaces are undercut so that their corners overhang the base as shown at a.

I have shown in my former application a base-plate having a flange at one edge thereof undercut in this manner while the other edge of said plate is provided with an upwardly extended flange as a part thereof to inclose one side of the rail. I have found that although such a form can be made between properly constructed rolls that a form such as shown and described in the present instance is much easier to form and some of the operations can be eliminated thus reducing the cost of manufacture.

At each side of the rail, which is positioned at about the middle of the plate is a splice-bar. These splice-bars are indicated by D and D' and are duplicates in that they are both sheared or cut from a single bar formed between rolls. Each consists of a vertical extension and a substantially horizontal extension the former adapted to fit snugly between the head and base of the rail, the latter adapted to rest upon the base of the rail; and each bar is extended beyond the rail-base and lies between the rail and the flanges C and C' of the base before described. The extended edge of the bar D' is provided with an angled face to fit the undercut surface of the flange C' and in consequence of being duplicates the opposite one D' is necessarily of the same form although a particular form of this said splice-bar D is not important as to the angled face mentioned but since both are cut from the same bar it will necessarily be of the form shown.

At one or more places the splice-bars are provided with notches in their edges adjacent to the flanges C and C'. One of these notches is shown in Figs. 4 and 5 at E' and also in Fig. 7 at E. They are formed in the edges of the horizontal extensions which lie adjacent to the flanges C and C' and immediately beneath them in the base plate holes F are punched and in the holes and the notches C are inserted wedge shaped bolts G whose upper threaded ends extend through blocks H and are provided with nuts J to tighten them; the form and arrangement of this type of bolt having been described in my former application and I lay no claim thereto herein per se. Into each hole F and notch E' at the

opposite sides of the device, as shown in Figs. 1 and 2 are inserted members or blocks K. The outer surface of each member, that is to say, that side thereof adjacent to the flange C' is beveled to fit snugly against the undercut surface of said flange.

The construction and office of the wedge shaped bolts is well understood but I shall describe their operation herein in order to 10 make the advantage to be gained from the present arrangement fully understood. Since the bolts are in fact wedges and bear against the undercut flange C they are caused to move toward the rail as the nuts J are tightened and in bearing against the splice-bar D force that member toward the rail thereby moving the rail toward and against the splice-bar D' carrying that member firmly 15 against the overhanging flange C', which securely holds it so it can have no vertical movement whatever. Having now provided for preventing vertical movement of the bar D' it is next important that there be no longitudinal movement thereof relative to 20 the base-plate. This is provided for in the use of the blocks K which have a position within the notches E' already mentioned so that in effect the splice bar D' and the base plate are as though they were one member 25 or unit while giving the advantage of easy construction by being separate parts.

The bolts G by having their position within the notches E of the splice-bar D prevent longitudinal movement of that member so 30 that all of the various parts are in effect locked relatively. Extensions or lugs K' of the blocks K rest upon the flange C' so that said blocks cannot drop through and leave their positions.

40 It is well understood that the side thrusts of the wheels of the train upon the rail tends to rack the splice and its parts with the result that the parts become loosened and the splice-bars in the present case in the absence 45 of some form of holding means would receive more or less movement in the direction of their lengths and relative to the base-plate which would result in disarranging the parts but since the bolts G on the one hand and 50 the members or blocks K on the other hand effectively lock the splice-bars relative to the base there can be no movement of any of the parts and since there is no movement of the splice-bars there is nothing to cause the bolts 55 L to become loosened.

60 My splice as constructed is very easily assembled. The base-plate is first placed in position at the joint of the rail with substantially the same projection at each side of the latter. The splice-bar D' is then dropped into position after placing the blocks K in their seats in the notches and holes provided therefor. The bar D is then inserted, the bolts G put in place and the usual bolts L placed through the bars and the rails and

when tightened all of the parts are firmly clamped in proper relation; the base-plate being afterward properly spiked to the ties in the usual manner.

The holes F and F' in the base may be 70 punched so that they coincide with the inner face of the flanges C and C' as shown in Figs. 5 and 7 or for convenience in punching they may be placed slightly inward from the flanges where they can be more conveniently 75 reached by the punch and without damage to the flanges in which case the block K is provided with an off-set as shown in Fig. 5, and a member M, Fig. 7, may be placed between the bolt G and the flange C to take 80 the pressure of said bolt, this however is merely a structural detail.

All the parts of my improved splice may be formed between rolls including the members K which may be obtained by rolling a 85 bar of the desired form of cross section from which pieces of the proper size can be cut or sheared to fit the holes F'.

The whole purpose of my invention, as may be seen is to form the base and splice-bars of separate parts acting in the capacity 90 of a single member or unit and to provide a form of means by which both splice-bars are absolutely prevented moving in a longitudinal direction relative to the base-plate. 95

Having thus described my invention, I claim:

1. The combination with the rail, of a supporting base-plate therefor provided with an upwardly extending projection at one side of the place of the rail and undercut in its inner surface, a member interposed between the projection and the rail, and adapted to enter said undercut, means extending through the member and base-plate to hold both of them 105 relatively rigid, a member at the opposite side of the rail, and means to clamp both members and the rail together and to hold the first described member against the projection of the base-plate.

2. The combination of the rail, of a supporting base-plate therefor provided with an upwardly extending projection at one side of the place of the rail and undercut on its inner surface, a member interposed between the projection and the rail and adapted to enter said undercut and fill the space between said projection and the rail, means extending through and carried by the member and the plate to prevent movement of these 110 parts relatively, a member at the opposite side of the rail, and means carried by the plate to clamp the members and rail and hold the first described member against the projection.

3. The combination with the rail, of a supporting base-plate therefor provided at each side of the place of the rail with an upturned extension one of which is undercut on its inner face, a member interposed between each 115

extension and the rail and both adapted to fit the rail, one of them adapted also to enter and fit the undercut extension, means extending through the last named member and the plate and carried by the latter, and means to clamp both members and the rail together and hold one of the members in engagement with the said undercut extension.

4. The combination with the rail, of a supporting base-plate therefor provided at one side of the place of the rail with an upturned extension undercut on its inner surface, a member interposed between and snugly fitting the extension, a device to prevent longitudinal movement of the member and the base-plate relatively, a member at the opposite side of the rail, and a device adapted to hold both members and the rail in close relation and also to hold the first described member against the undercut extension.

5. The combination with the rail, of a supporting base-plate having an upturned flange at each side of the place of the rail one of them having an undercut inner face, a member positioned between the rail and flange and having a beveled face adapted to fit the undercut surface of said flange, means extending through the member and the plate to prevent their movement relatively, a member between the opposite side of the rail and the flange at that side, and means to move the members and the rail in the direction of the said undercut flange.

6. The combination with the rail, of a supporting base-plate having an upturned flange at each side of the place of the rail each of which is undercut on its inner face, a member having a position between the rail and one of

the flanges and prevented having vertical movement by the said flange, means extending through and carried by the member and the base-plate for preventing the movement of the two relatively, a member having a position between the rail and the flange at the opposite side of the plate, and means to engage the member and the flange and adapted to hold the said member and the plate relatively rigid, and also to clamp all of the parts and the rail in rigid relation.

7. The combination with the rail of a supporting base-plate having an upturned flange at each longitudinal edge and both undercut on their inner faces, a member having a position between the rail and one of the flanges and adapted to fit into its undercut face and prevented thereby from having vertical movement, there being a notch in the member adjacent to the flange and a hole in the base-plate beneath the notch, a member positioned within the same, a member positioned between the rail and the opposite flange, there being a notch in the member adjacent to the flange and a hole in the base-plate beneath the notch, and a bolt having a wedged shape portion to engage the member and the flange for preventing the movement of the member and the base-plate relatively, and adapted when tightened, to clamp the rail and all the parts in rigid relation.

In testimony whereof I affix my signature, in presence of two witnesses.

JAMES THOMAS.
